UNITED STATES PATENT OFFICE.

JAMES W. SHERIDAN, OF CHICAGO, ILLINOIS, ASSIGNOR TO WOODS MOBILETTE COMPANY, OF CHICAGO, ILLINOIS, A CORPORATION OF ILLINOIS.

DESIGN FOR AN AUTOMOBILE-BODY.

53,380.

Specification for Design.

Patented May 27, 1919.

Application filed December 4, 1916. Serial No. 135,091. Term of patent 3½ years.

To all whom it may concern:

Be it known that I, JAMES W. SHERIDAN, a citizen of the United States, residing at Chicago, in the county of Cook and State of Illinois, have invented a new, original, and ornamental Design for an Automobile-Body, of which the following is a specification, reference being had to the accompanying drawing, forming part hereof.

The drawing shows a plan view of an automobile body.

I claim:

The ornamental design for an automobile body, as shown.

JAMES W. SHERIDAN.

Witnesses:

JNO. C. LONG,
E. A. SHERIDAN.
